CENTRIFUGAL PUMP

Charles J. Bergh, Vandalia, Ohio, assignor to The Dayton Pump & Mfg. Co., Dayton, Ohio, a corporation of Ohio

Application December 21, 1950, Serial No. 202,106

4 Claims. (Cl. 103—103)

1

This invention relates to centrifugal pumps for delivery of liquids under pressure.

An object of the invention is to provide a simplified pump structure that is more easily assembled and which is directly connected with the driving motor for the pump.

Another object of the invention is to provide a centrifugal pump wherein a pump body is constructed and arranged in such a manner that it is capable of receiving pump parts of different size whereby to produce a pump having different capacities.

Still another object of the invention is to provide a centrifugal pump in accordance with the foregoing object wherein there is provided a removable volute member that can be replaced by volute members of other size and cooperating impellers whereby pumps of different capacity can be obtained utilizing a single basic pump body.

Still another object of the invention is to provide an improved construction of a centrifugal pump wherein the seal member for sealing the drive shaft connected with the impeller of the pump is positioned within a chamber filled with the pumped liquid in an arrangement whereby foreign particles harmful to the seal are collected in a manner to avoid contact with the seal and thereby prolong its life.

Still another object of the invention is to provide a centrifugal pump in accordance with the foregoing objects wherein a part of the pump body forms a part of the housing for the electric motor that drives the pump.

Another object of the invention is to provide a centrifugal pump in which the movement of liquid through the pump removes air from the pressure chamber of the pump to prevent the same from becoming air bound, the liquid stream having a suction or Venturi action in drawing air from the pressure chamber into the stream discharging from the pump body.

It is another object of the invention to provide a centrifugal pump having a continuous prime.

Further objects and advantages will become apparent from the drawings and the following description.

In the drawings:

Figure 1 is a side elevational view with the pump body broken away and with the pump shown in cross-section along line 1—1 of Figure 2, the pump incorporating features of this invention.

Figure 2 is a cross-sectional view taken along line 2—2 of Figure 1.

Figure 3 is a cross-sectional view taken along line 3—3 of Figure 1.

2

Figure 4 is a cross-sectional view taken along line 4—4 of Figure 1.

Figure 5 is a side elevational view of the removable volute member of the pump.

Figure 6 is a plan view of the removable volute member for the pump.

Figure 7 is a perspective view illustrating the assembly of the removable volute and impeller within the pump.

Figure 8 is a cross-sectional view taken along line 8—8 of Figure 1.

In this invention the pump body 12 is mounted on a base 10 by means of bolts 50, the base 10 in turn being supported upon a bed 11, which may be a concrete foundation.

The base 10 supports the pump body 12 which is in the general form of a cylindrical casing closed at one end by a wall 13. The opposite wall of the pump body 12 consists of a closure plate 15 that is secured to the body 12 by means of bolts 14. The closure plate 15 has a wall 51 that projects from the plate 15 and is arranged substantially in the form of a cylinder, thereby providing a chamber 52. The wall 53 closes one end of the chamber 52, and also thereby closes the pump body 12. This wall 53 forms one end wall of the housing 16 comprising a part of the electric motor, the wall 53 being secured to the housing 16 by suitable bolts.

The motor 16 drives a shaft 17 that extends through the closure wall 53.

Within the pump body 12 there is a pump housing 18 defined by a wall 19 projecting inwardly of the pump body from the wall 13 forming a cylindrical portion. From the wall portion 19, the wall flares radially outwardly in a substantially radial wall portion 21 extending toward the side wall of the pump body 12, this wall portion 21 turning into parallel spaced relation with the casing as a second cylindrical portion 22, and finally merging with the in-turned portion 23 constituting a flange on the inner end of the body 12. The housing 18 has radially disposed protuberances 24, some of which are joined to the pump body 12, which receive the bolts 14 by which the body 12 is attached to the closure plate 15. The pump body 12 and the pump housing 18 thereby define a pressure chamber 25.

The pump housing 18 forms a substantially cylindrical chamber 54 that receives a removable volute member 26.

The removable volute member 26 is more particularly illustrated in Figures 5 and 6 and consists of a radially disposed plate 55 that has an axial opening 56 therein. Around the opening 56 there is provided a wall 28 that defines a

55

50

55

pressure chamber 29. The wall 28 of the volute 26 forms a tangentially disposed outlet passage 57 from the pressure chamber 29 that curves to a radial discharge opening 57a. The wall 28 is also provided with flange portions 58 on opposite sides of the discharge opening 57a that engage the wall portion 22 on opposite sides of the discharge outlet 59 provided in the wall 22 of the pump housing 18, thus effectively sealing liquid from discharge between the flanges 58 and the wall 22.

The wall 28 of the volute member 26 engages the wall portion 21 of the pump housing 18 and cooperates therewith to form the pressure chamber 29 in which the impeller 32 is placed.

The impeller 32 is secured on the threaded end 60 of the motor shaft 17, the end 60 being threaded in a direction opposite to that of rotation of the impeller to retain the impeller on the shaft 17. The impeller 32 is generally of conventional construction, being provided with an axial eye opening 33 to receive fluid and directional vanes 34 and impeller vanes 35 to carry fluid radially outwardly and discharge it into the pressure chamber 29. From the pressure chamber 29, the fluid is delivered through the passage 57 and thence through the opening 57a and through the discharge outlet 59 into the discharge pipe 42. The wall 22 being spaced a short distance from the pump body wall 13 provides an open passage 25a in the chamber 25 across which fluid flows from the discharge outlet 59 to the discharge pipe 42. The discharge pipe 42 being in substantially linear alignment direct flow relationship with the discharge outlet 59 and opening 57a and generally of larger size than the discharge opening 57a provides for a straight through flow of fluid from the opening 57a to the pipe 42.

The fluid crossing the passage 25a communicates with the pressure chamber 25 and fills the same with fluid. Also, since the discharge pipe 42 is in direct alignment with the opening 57a, and is placed at the top of the chamber 25, the liquid flowing over the open passage 25a produces a suction or Venturi action between the outlet 59 and the pipe 42 which draws from the chamber 25 any air that tends to collect in the top of the chamber 25 and discharges the air through the pipe 42 with the liquid therein. The chamber 25 is therefore permitted to fill completely with liquid so that a continuous prime is provided for the impeller and the possibility of the chamber 25 becoming air bound is removed. Liquid in the chamber 52 is also a part of the active system to provide a continuous prime for the impeller.

The eye opening 33 of the impeller is defined by a spindle portion 36 rotatable in a bearing 37 carried in the cylindrical wall portion 19 of the pump housing 18.

The removable volute member 26 has the radial wall 55 thereof positioned with the periphery of the wall in engagement with the inner periphery of the wall 22 of the pump housing 18, thereby coaxially aligning the volute member 26 within the cylindrical chamber 54, which is also coaxial with the cylindrical portion 19 of the pump housing 18. Radial flanges 62 on the volute member 26 aid in proper location of the volute member in the chamber 54.

The volute member 26 is also provided with an annular protuberance 65 that engages a cooperating annular protuberance 66 on the closure plate 15 whereby the volute member 26 is held in

position in the chamber 54 by the closure plate 15 and the chamber 52 is thereby effectively sealed from the pressure chamber 25. A second annular protuberance 67 on the closure plate 15 engages the inner periphery of the flanged wall portion 23 for coaxial location of the closure member 15 relative to the axis of the pump housing 18. A pin 10 extends between the closure plate 15 and the removable volute member 26 to retain the volute member in position with the passage 57 in alignment with the opening 59, and to prevent rotation of the volute member within the chamber 54 for assembly of the pump structure.

15 A seal member 70 is provided around the drive shaft 17 and consists of a stationary seal element 71 placed in the wall 53 of the closure plate 15 and a running seal element 72 that is urged against the stationary member 71 by a spring 73. Thus, liquid in the chamber 52 is prevented entry into the housing of the motor 16.

Fluid is admitted to the pump through the inlet opening 38 provided in the end wall 13 of the pump body 12, the opening 38 being aligned with the cylindrical wall portion 19 of the pump housing and the eye 33 of the impeller 32. Discharge from the impeller flows through the passage 57 into the registering discharge outlet 59 in the wall 22 and thence across the narrow intervening part of the chamber 25 to the radial opening 41 in the pump body 12 and into the discharge pipe 42 as heretofore described, fluid within the chamber 25 providing a continuous prime for the impeller.

35 It may be desirable at times to use the centrifugal pump in combination with a jet booster. For this purpose the end wall 13 of the pump body 12 is provided with an opening 44 that may be connected with a pipe for delivery of fluid under pressure from the chamber 25 to a jet booster placed within a well.

40 The centrifugal pump of this invention is constructed in such a manner that a complete series of pumps of different capacities can be obtained, utilizing the single pump body 12 and the closure plate 15 as the basic elements. It will be noted that the wall 28 of the removable volute member 26 is placed radially inwardly of the outer periphery of the flanged wall 55 of the volute 26. With an impeller 32 of proper size placed within the pressure chamber 29 formed by the wall 28, a pump of given capacity is produced, the size of the impeller governing the pumping capacity.

45 Merely by removing the volute 26 and the impeller 32 of the pump of Fig. 1 and replacing the same with another volute in which the wall 28 thereof is placed closer to the outer periphery of the flanged wall 55 and another impeller of larger size to cooperate with the enlarged pressure chamber formed by the radially outward position of the wall 28, a pump of increased capacity can be made. It will of course be understood that as the pump capacity is increased, motor horsepower should also be increased accordingly.

50 The construction of the centrifugal pump of this invention, therefore, permits a manufacturer to produce the two major components of the pump, comprising the pump body 12 and the closure plate 15 as standard elements and to offer the consumer pumps of different capacities merely by changing the volute 26 and the impeller 32.

55 In fact, after a pump has been delivered to a customer, and the customer desires greater

pumping capacity, he is in a position to obtain the same merely by purchasing from the manufacturer a volute 26 and an impeller 32 of increased size that he can place in the pump body, thus saving the expense that would be required to purchase a completely new pump.

The chamber 52 in which the seal 70 is located is in open communication with the pressure chamber 29 of the volute 26 through the opening 56 through which the impeller 32 is installed into the pump housing 18. Thus, the chamber 52 will be filled with fluid that is being pumped, but since the fluid is discharged generally radially outwardly of the impeller 32, the fluid in the chamber 52 will be more or less quiescent. Thus, any foreign particles that enter the chamber 52 can settle to the bottom of the chamber rather than collecting on the seal 70, thus greatly prolonging the life of the seal member.

While the apparatus disclosed and described herein illustrates a preferred form of the invention, yet it will be understood that mechanical alterations can be made without departing from the spirit of the invention, and that those modifications that fall within the scope of the appended claims are intended to be included herein.

Having thus fully described my invention, what I claim as new and desire to secure by Letters Patent, is:

1. An impeller pump, comprising, a hollow pump body of generally tubular shape and having a closure wall at one end thereof transverse of the axis of the pump body, a second wall interiorly of said body having a first portion generally transverse of the axis of said body and a second portion generally axial of the axis of said body and connecting with said body and forming a pumping chamber within said body open at one side thereof, a discharge opening at the top of said pump body, said second portion also having a discharge opening in alignment with said first mentioned discharge opening to permit fluid flow therebetween, a volute member having a first wall portion lying in a plane disposed radially of the axis of the member and a second volute wall portion around the axis of the member and perpendicular to said frame, said volute member being removably positioned in said pumping chamber with the radial wall thereof engaging said pumping chamber wall to axially position the volute member in the pumping chamber and with the second volute wall portion engaging the pumping chamber wall to form therewith a volute chamber within said pumping chamber of smaller cross-sectional area than said pumping chamber, an impeller within said volute chamber, and a closure wall on said body enclosing said volute member within said pumping chamber.

2. An impeller pump, comprising, a hollow pump body of generally tubular shape and having a closure wall at one end thereof transverse of the axis of the pump body, a second wall interiorly of said body having a first portion generally transverse of the axis of said body and a second portion generally axial of the axis of said body and connecting with said body and forming a pumping chamber within said body open at one side thereof and partitioning said body to form a pressure chamber therein, a discharge opening at the top of said pressure chamber, said axially arranged portion of said second wall being spaced from said discharge opening and having a discharge opening therein in substan-

tial linear alignment with the first mentioned discharge opening but spaced therefrom for flow of liquid between the said discharge openings across a portion of said pressure chamber at the top portion thereof, a volute member having a wall portion generally radial of the axis of the member and a second volute wall portion around the axis of the member, said volute member being removably positioned in said pumping chamber with the radial wall thereof engaging said pumping chamber wall to axially position the volute member in the pumping chamber and with the volute wall portion engaging the pumping chamber wall to form therewith a volute chamber within said pumping chamber of smaller cross-sectional area than said pumping chamber, an impeller within said volute chamber, and a closure wall on said body enclosing said volute member within said pumping chamber.

3. An impeller pump, comprising, a hollow pump body of generally tubular shape and having a closure wall at one end thereof transverse of the axis of the pump body, a second wall interiorly of said body having a first portion generally transverse of the axis of said body and a second portion generally axial of the axis of said body and connecting with said body and forming a pumping chamber within said body open at one side thereof, a discharge opening at the top of said pump body, said second portion also having a discharge opening in alignment with said first mentioned discharge opening to permit fluid flow therebetween, a volute member having a first wall portion generally radial of the axis of the member and a second volute wall portion around the axis of the member, said volute member being removably positioned in said pumping chamber with the radial wall thereof engaging said pumping chamber to axially position the volute member in the pumping chamber and with the volute wall portion engaging the pumping chamber wall to form therewith a volute chamber within said pumping chamber of smaller cross-sectional area than said pumping chamber, an impeller within said volute chamber positioned therein through said opening in said radial wall of said volute member, a closure wall on said body enclosing said volute member within said pumping chamber and forming an axially arranged chamber adjacent the opening in said volute member and a shaft seal structure in said last mentioned chamber between said impeller and a wall of said last mentioned chamber.

4. An impeller pump, comprising, a hollow pump body of generally tubular shape and having a closure wall at one end thereof transverse of the axis of the pump body, a second wall interiorly of said body having a first portion generally transverse of the axis of said body and a second portion generally axial of the axis of said body forming generally a tubular structure connecting said first portion with said closure wall axial of said body and forming a fluid passage and a third portion at the opposite side of said first portion and connecting with said body and forming a pumping chamber within said body open at one side thereof, said second wall partitioning said body to form a pressure chamber therein with said third portion having a discharge opening connecting with said pressure chamber, means forming a discharge opening from said pressure chamber, a volute member having a wall portion radial of the axis of the

volute member and a second volute wall portion around the axis thereof, said volute member being removably positioned in said pumping chamber with the radial wall thereof engaging said pumping chamber wall to axially position the volute member in the pumping chamber and with the volute wall portion engaging the pumping chamber wall to form therewith a volute chamber within said pumping chamber of smaller cross-sectional area than said pumping chamber, an impeller within said volute chamber having an axially extending portion positioned within said second portion of said second wall for flow of liquid to said impeller, and a closure wall on said body enclosing said volute member within said pumping chamber.
